FINGER GUARD FOR SEWING MACHINES

Frank Damiano, Newburgh, N. Y.

Application April 16, 1940, Serial No. 329,975

1 Claim. (Cl. 112—261)

This invention relates to a finger guard for sewing machines of various types, and has for the primary object the provision of an efficient and inexpensive device of this character which may be easily installed on the stem of a presser foot of a sewing machine for movement therewith and may be easily adjusted into an operative position about the needle of said machine to prevent the operator from getting any one of the fingers or thumb into the path of the needle and consequently obviate any possibility of the operator being injured by the needle and may be easily moved into an inoperative position entirely clear of the needle so that threading of the needle may be easily carried out and other adjustments to said needle and associated parts without interference by the device.

With these and other objects in view, the invention consists in certain novel features of construction, combination and arrangement of parts to be hereinafter more fully described and claimed.

For a complete understanding of my invention, reference is to be had to the following description and accompanying drawing, in which

Figure 1 is a rear elevation illustrating a fragmentary portion of a sewing machine including a presser foot and needle mechanism with a needle guard associated therewith and constructed in accordance with my invention.

Figure 2 is a sectional view taken on the line 2—2 of Figure 1.

Figure 3 is a perspective view illustrating the finger guard.

Figure 4 is an end view of a thread cutter.

Figure 5 is a sectional view taken on the line 5—5 of Figure 1.

Referring in detail to the drawing, the numeral 5 indicates a presser foot of a sewing machine and 6 the needle of said sewing machine. The presser foot includes the usual stem 7 on which the present invention is mounted so as to be movable into and out of the path of movement of the needle 6.

Secured on the stem 7 of the presser foot 5 is an adjustable split supporting collar 8 held in position by a set screw 9. The supporting collar may be adjusted upwardly and downwardly on the stem 7 to meet with conditions of properly mounting the present invention for operation in conjunction with the needle 6.

The collar 8 includes hinge barrels to receive a hinge pin 9' acting to support on said collar a finger guard 10 and a thread cutter 11. The hinge pin 9' has a grooved end to be engaged

by a portion of the cutter 11 for securing the pin against displacement.

The thread cutter 11 includes a cutting plate 12 having a V-shaped notch 13 formed in the upper edge thereof. The cutter further includes a bottom plate 14 integral with the cutting plate 12 and has its end portions bent at right angles thereto and extending upwardly at the ends of the cutting plate 12 and terminating in a plane thereabove to form guide elements 15 for the purpose of guiding a thread into the cutting notch 13 of the cutting plate. One of the guide elements 15 engages the grooved end of the pin 9' and may be flexed therefrom when desiring 15 to remove the pin 9'. The apertured ear rests upon the top face of one of the hinge barrels of the supporting collar 8, as clearly shown in Figure 1.

The finger guard 10 consists of a grill-work 20 17 formed integrally with a supporting arm 18. The free end of the supporting arm which is positioned laterally of the grill-work is provided with a barrel 19 to receive the hinge pin 9' thereby mounting the arm for hinging movement on 25 the supporting collar 8. The cutter is secured to the barrel 19 by means of a lug 16 soldered or welded to the barrel as well as to one of the guide elements 15. One portion of the arm 18 is arcuately curved, as shown at 20. Secured to 30 the arm 18 substantially intermediate its ends is a metallic strip 21 including an arcuate shaped portion 22 to coact with a portion of the arm and the curved portion of the latter in providing to the finger guard an upper rim of substantially U shape. A portion of the strip 21 extends at right angles to the arm 18 and forms a spring catch 23 to engage with the stem 7 of the presser foot for retaining the guard 10 in position about the needle 6 to prevent a person's fingers from 35 coming into the path of movement of the needle. The catch 23 is capable of flexing so that when pressure is placed upon the arm 18 or the finger guard, the latter may be swung away from the needle by the catch 23 riding off the stem 40 7 of the presser foot. When the guard is in the latter-named position the needle 6 is freely exposed to permit threading thereof and other adjustments. When the guard is positioned to protect the operator from the needle it overlies the 45 presser foot and within the confines of said presser foot. It is to be noted that one side of the guard is fully open which will permit the guard to be readily swung into operative and inoperative positions with respect to the needle.

While it has been stated and shown that the

guard is of grill-work construction, it may be of a solid transparent construction if so desired.

It is believed that the foregoing description, when taken in connection with the drawing will fully set forth the construction and advantages of this invention to those skilled in the art to which such a device relates, so that further detailed description will not be required.

Having thus described the invention, what I claim is:

In a finger guard for a sewing machine needle, a supporting arm having a compound curvature and an arcuately curved end portion and a second end portion of a hinge barrel shape, a strip secured to said arm and including right angularly disposed end portions and one of said

end portions coacting with a portion of the arm and the arcuately curved end portion of said arm in forming a guard rim of substantially U shape, a guard construction open at one side formed on and depending from the guard rim, and an adjustable attaching clamp for application to a presser foot stem of a sewing machine and includes a hinged pin extending through the hinge barrel shaped end of said arm, one of said right angularly disposed end portions of said strip engageable with the presser foot stem to releasably secure the guard construction in operative position with relation to the path of movement of a needle of the sewing machine.

FRANK DAMIANO.
